(57) **CLAIM**

The ornamental design for a front cover and display for a mountable electronic navigation instrument, as shown and described.

DESCRIPTION

FIG. 1 is a perspective view of the front cover and display for a mountable electronic navigation instrument of the present invention;

FIG. 2 is a front elevational view thereof;

FIG. 3 is a bottom plan view thereof;

FIG. 4 is a top plan view thereof;

FIG. 5 is a left end view thereof; and,

FIG. 6 is a right end view thereof.

The broken line showing is for illustrative purposes only and forms no part of the claimed design.

UNITED STATES PATENT AND TRADEMARK OFFICE
Certificate

Patent No. D 453,481 S

Patented: February 12, 2002

On petition requesting issuance of a certificate for correction of inventorship pursuant to 35 U.S.C. 256, it has been found that the above identified patent, through error and without any deceptive intent, improperly sets forth the inventorship.

Accordingly, it is hereby certified that the correct inventorship of this patent is: Brian G. Schoenfish, Kansas City, KS; David Laverick, Overland Park, KS; and Christopher Hanshew, Lenexa, KS.

Signed and Sealed this Fourteenth Day of October 2003.
